UNITED STATES PATENT OFFICE.

WILLIAM F. LAUTENSCHLAGER, OF CINCINNATI, OHIO, ASSIGNOR TO THE PEERLESS MACHINERY COMPANY, A CORPORATION OF MASSACHUSETTS.

PERFORATING MACHINE.

Application filed November 28, 1924. Serial No. 752,579.

To all whom it may concern:

Be it known that I, WILLIAM F. LAUTENSCHLAGER, a citizen of the United States, and residing at Cincinnati, in the county of Hamilton and State of Ohio, have invented a new and useful Perforating Machine, of which the following specification is a full disclosure.

This invention relates in general to 10 punching or perforating machines, and particularly to improvements in automatic perforators ordinarily used for punching openings in shoe parts, such as uppers, vamps, tips, etc., but also used for other classes of 15 goods and on other materials. The herein machine, although used for punching or cutting a line of perforations, generally adjacent the edge of a flat shoe part, glove or sweat band, is particularly adapted for 20 punching closed vamps of annular configuration.

The difficulty experienced in punching closed vamps on "cylinder arm" machines of the right hand type is due to the fact that 25 the work is presented to the punching instrumentalities over the left end of the cylinder arm, and that the body of the vamp hangs downwardly at right angles to that portion of the vamp being perforated, which 30 causes strain, or catches on the arm and assumes unnatural strained position, entirely 35 different from the position which the body of the vamp assumes when it is presented from the right and is allowed to lie naturally 40 in the space between the punching instrumentalities and the column of the frame. These difficulties occur particularly when 45 the throat portion is approaching or is adjacent the punch, where sharp turning or flattening is necessary. In this instance the goods must be unnaturally twisted or buckled to cause the same to assume the proper position or relation to engage for advancement by the punch. On the ordinary 50 commercial types of machines now in use, a work arm or support extends from the column to the left over the base and in order to obtain sufficient rigidity the arm is generally of relatively large diameter, consider- 55 ably greater than the diameter of the throat.

portion of the closed vamp, and therefore, this portion abuts the arm in an unnatural manner resulting in buckling or twisting and therefore in hindrance to the proper feeding of the goods. 55

My machine eliminates the above enumerated inconveniences by providing a work support as an arm extending upwardly from the base with the outer or work end overhanging and spaced upwardly from the base 60 and away from the column and so constructed and positioned or faced as to provide a free working space on all sides of the supported punch and above and beneath the same, permitting the goods to hang naturally thereover and be freely manipulated and turned or lifted, with particular ease when the throat or heel portions are approaching the punch.

The main object is to provide a right hand 70 perforating machine particularly adapted for perforating closed or sewed shoe vamps, and providing ample clearance at all sides of the work support, and also providing an arrangement of the support with reference 75 to the other parts of the machine, particularly the column, such as to allow the vamp to be introduced upon or about the work support from the right hand side thereof, between the support and the column or mechanism supporting element, thus permitting the use of the right hand for this placing or introduction of the goods, and permitting the punching operation to be completed by 80 both hands, or if desired, principally by 85 use of the left hand, leaving the right hand free to operate the pulley, when necessary.

Another object is to provide a machine of the character mentioned, for general use, but particularly adapted for punching closed 90 vamps which are difficult to properly manipulate, especially when punching at the throat or heel portion, and most difficult when the throat is of narrow dimension.

Another object is to provide a machine in 95 which the paper used under the material to receive the punch impacts, is fed in the same direction as the work.

Another object is to arrange the paper 100 with respect to the work arm so that there

will be no interference between the work and the moving paper, when the work is hung on the work support.

In the machine of the "arm" type in which an arm extends horizontally from the column toward the left and the outer unsupported end receives the punch impacts and wherein a plate must be attached to the arm for flat work, and a smaller plate used for closed work, the paper has been made to travel at a right angle to the direction of feed. It has been claimed that interference between work and paper could not be prevented if the paper traveled in the same direction with the work, on a machine adapted for punching closed vamps, particularly when starting the punching operation at the heel seam. The herein machine, however, provides for the unobstructed feed of the paper in the same direction as the goods and with economy of paper.

Another feature of the invention in addition to that permitting right hand introduction of the work over the work table, is the general structure of the frame and the particular manner of reinforcing the same by a double rib extending from a point within the work support below and along the base, upwardly within the hollow column and along the lower side of the hollow punch supporting arm. This reinforcing feature is of prime importance inasmuch as it combines lightness with sufficient rigidity of the reinforced parts to prevent deformation incident to punching strains.

In the ordinary commercial types of right hand machines, the generally approved type, (so called because the pulley is at the right and in a most convenient position for control by the right hand as the operator faces the machine) the work supporting arm extends from the main frame toward the left and therefore in the same direction as the punch supporting and operating arm. In the present machine, however, the punch supporting and work supporting arms extend in opposite directions.

In certain types of commercial machines now in use a removable work plate is employed which is attached to the work arm when flat material is being punched, the plate being attached to this work supporting arm which extends from the main frame in the same direction as the arm which supports the punch and operating mechanism therefor. When closed or annular work is used this plate is removed and a smaller plate substituted and the work introduced over the same from the left end of the machine and hung upon the arm and over the substituted plate, while being manipulated, fed and punched. Moreover, in order to obtain sufficient rigidity of the arm, the same is generally of such large cross sectional dimension that when working at the throat

portion of the vamp, the same engages the arm in such manner as to obstruct the feed and, as before mentioned, to overcome it, it is necessary to raise or buckle the goods in front of the punch, this raising or buckling being necessary at both throat and heel portions, and particularly objectionable.

Other objects, features and certain advantages will be pointed out in the description and drawings forming a part of this application, and in said drawings:

Figure 1 is a side elevation of my improved punching machine.

Figure 2 is an end view looking at the work end of the machine.

Figure 3 is a horizontal section viewing the work support, in plan, and showing a closed vamp positioned thereon, as when beginning the punching operation from the heel or sewed end thereof, and illustrating how the improved angularly related work arm assists in guiding the goods, the position of the left hand being shown in dot and dash lines.

Figure 4 is a fragmentary view similar to Figure 1 showing a closed vamp positioned upon the work arm, as when operating at the throat portion, and illustrating the clearance between the vamp and other portions of the machine.

Figure 5 is a plan of Figure 4, further illustrating the unobstructed relation of the work to the other parts of the machine, the position of both hands of the operator being shown in dot and dash lines.

The present machine is an improvement over that class of perforators or punching machines shown in Patents Nos. 773,329, 765,087 and 843,899, to William F. Lautenschlager, but relates principally to the arrangement of the work pedestal, punch block and paper guiding and feeding devices adjacent the pedestal, said guiding and feeding devices being arranged to conform with the arrangement and structure of this improved work support or pedestal. Therefore only so much of the other working parts of the machine are shown as seems necessary for a clear understanding of the features of the present improvement.

The general shape of the machine, when viewed from the front or working side, approximates that of a reverse letter G, the over-hanging punch head supporting arm and oppositely extending relatively short work support arm being in this design, related to the work support in the manner to suggest the shape. The essential feature, however, is that the arms and end faces thereof extend and face in relatively opposite directions the outer end face of the arm toward the left, and the inner end face of the work support to the right, with the result that closed work can be introduced over the work support or arm from the right, a

relatively large open space being provided between the inner end face of the work arm and the vertical portion of the frame of which the punch head supporting arm is a continuation. Thus the goods may lie between the inner side of the work support and the other portions of the frame, and may be freely manipulated by either or both hands, raised and flattened without interference with any other part of the machine thus eliminating the necessity for buckling or unnaturally twisting the goods during any portion of the punching operation.

This present machine also eliminates the use of the work plate ordinarily employed and provides for unobstructed manipulation upon both flat and closed vamps.

The frame is formed in a single piece as a hollow casting suitably strengthened by ribs to adequately withstand the usual operating strains. The frame comprises four principal portions, a horizontal three-sided upwardly curved base 1, adapted to be attached to the table; a vertically disposed column 2 in which portions of the operating mechanism are housed; an over-hanging punch supporting and operating arm 3, as a forward extension of the column for operatively supporting the punch; and a work supporting arm 7 extending upwardly from the base and curving toward the column to overhang the base. At the outer vertical face of the arm 3 are mounted the cross reciprocating frame 5 and the vertically reciprocating punch spindle 6, and these parts are connected by the usual transmission mechanism in a manner substantially similar to the patents above referred to. The general punching and feeding operations of the present machine in no way differ from that of the patents mentioned.

This vertically and horizontally extending rigid work support or arm 7 has a portion of its upper flat surface 9 underlying the punch spindle and adapted to hold the work and permit unobstructed manipulation thereof during punching operations.

The arm or work support is of concavo-convex configuration, as viewed in side elevation, see Figures 1 and 4, with its concave inwardly directed side 10 facing the vertical wall 11 of the column 2 forming a relatively short overhanging arm extending in the direction of the column. The outer or convex side 12 curves outwardly and downwardly toward the base 1. The flat horizontally disposed work face 9, of which the concave side is substantially a continuation, provides a support for the work and hand, shaped to obtain a convenient rest or support for it.

The degree of concavity of the inner side 10 of the arm, and therefore the depth of the recess determines the extent of overhang of the arm, may be changed, made

greater or less, and is required to give clearance for the hand between the work and the paper, permitting the paper guiding rolls 20 to lie substantially beneath the punch block 15 and over-hanging portion 70 of the work arm or support.

The upper inner end of the work support is notched crosswise at its inner end, as at 13, to form a seat for receiving the punch block 15, and said block is secured in place by a screw 16, extending upwardly from beneath. The long dimension of the block lies in a direction of the feed and the same is vertically grooved as at 17 at each end to provide guides for the tape P which receives the punch impacts to prevent dulling of the punch, and which is fed across the block with the work and in the same direction as the work. The work support is offset laterally, relative to the long axis of the frame, see Figures 2, 3 and 5, to provide substantially parallel inclined surfaces, respectively 19, 21, at the rear and front sides, and slanting toward the front or working side of the machine. The combination of the lateral offset and convex curvature above referred to permits the outer portion of the pedestal to be conveniently grasped by the left hand of the operator when the goods is between the hand and the pedestal. The degree of lateral offset and its relation to the direction of feed is such that when working at the heel end of the closed vamp the goods may be bent flatly and naturally over the back edge of the support in such a manner as to dispose the finished or working edge of the work or vamp W in direction of the feed which is the natural "lay" of the goods.

No change of the punch block is necessary since the block serves for all varieties of work, thus doing away with this troublesome feature of changing or substitution, according to the variety of work.

Although by the lengthening or shortening of the heel portion of the vamp the angle between the counter and the working edge E may be slightly varied, the angular offset of the work support materially assists in placing the work naturally which, under these conditions, is usually held by placing the fore and middle finger upon the top of the work, the thumb beneath the work and against the front inclined side 21 of the work support, and the ring finger at the rear side and against the vertically disposed inclined wall 19 of the pedestal, this position of the hand being shown in dot and dash lines in Figure 3.

The lengthwise dimension of the work face 9 is such that the outer portion of the work generally overhangs the convex portion 12, and when operating flat work or at the throat portion of a closed vamp, the goods may be conveniently bent down-

wardly over and in conformity to the upper periphery of the pedestal.

Thus the work support, so to speak, rests upon the base and functions as a short arm curving upwardly and inwardly above the base toward the column and not as an arm extending from the column and therefore yieldable under working strains. My work support therefore has a rigidity under working strains heretofore unknown in this class of machine and this rigidity combined with the spaced relation of its inner or work end with reference to the vertical wall of the main column 8 provides for introduction of goods thereover from the right, and an unobstructed working space sufficient for the free manipulation of the goods.

The cross dimension of the work support is relatively small but the area of the work supporting face sufficiently great to furnish the proper rest for the goods, yet allow the same to lie dependingly at both sides, if desired.

Figures 4 and 5 illustrate the ease with which closed work may be manipulated when working at the throat portion T, the vamp being represented at W. It will be noted that the material surrounding the throat portion lies flatly against the upper side of the support while the remaining portion, including the heel or counter lies unobstructedly between the inner end or right face of the work support and the vertical wall 11 of the column, the space between these elements being sufficient to accommodate for work of maximum size. In Figure 5 the position of the hands is roughly indicated in dot and dash lines and shows the thumb of the left hand beneath the work lying against the forwardly inclined face 21 while the other fingers of the left hand lie above and upon the work. The front portion of the goods is grasped by the right hand with the thumb on top of the goods. Figures 4 and 5, thus well illustrate the manner and ease with which closed work, particularly closed vamps, may be manipulated. It will also be noted in Figure 3, when working at the seamed portion of the closed vamp, that the other portion of the vamp can lie looped about the work support without interference with the tape or paper P.

The base 1, see Figure 2, is three sided, the upper side 52, upwardly convexed, and the sides 53 vertically disposed and parallel. Laterally extending lugs 54 support the base, which is adapted to be inserted or placed in an opening 55 provided in the bench 56, and when so placed the lines or corners formed by the intersection of the curved top with the vertical sides, lie flush with the top of the table or bench. The top of the base thus lies slightly above the table and forms a continuation thereof eliminating obstructive

shoulders and leaving a free smooth pass for introduction of the work.

The tape feeding mechanism is located as shown in Figures 1, 2 and 3 and comprises a bracket 60 having a rearward extension or arm 61 and providing upper and lower bearings 62, 63, the upper of which has rotatably mounted therein a drive shaft 64 extending lengthwise of the frame and suitably connected with mechanism by which the shaft 75 is rotated to cause a feed of the tape in the direction of the feed of the goods.

The mechanism for operating the shaft 64 is not herein shown inasmuch as it is one of the general features illustrated in the 80 patents above mentioned. The shaft 64 has a roughened roll 65 keyed thereto and has a spur gear 66 keyed thereto meshing with the corresponding spur gear 67 keyed to a shaft 68 journaled at the upper end of an 85 adjustably swung frame 69 pivoted upon a shaft 70 held in the bracket 60. At the opposite end of the shaft 68 is a smooth surfaced roll 71 cooperating with the roll 65, the tape P passing between the rolls and being 90 fed in the direction of the arrows. In the operation of facing the tape the same is brought beneath the front roll of the paper guide, rolls 20 rearwardly thereon, upwardly to groove 17, over the punch block, downwardly in groove 17, from the opposite end of the block around the work support and around the second guide roller, between the rollers, and then upwardly and between the feed rolls. The operation of the tape is 95 obvious, the chief feature being the manner of disposing the upward and downward runs of the tape after passing upwardly to, over and downwardly from the work support, this arrangement being for the purpose of unobstructedly disposing the tape so the closed work may be hung upon the support, or work table, and so that sufficient space between the work and the tape may be had.

An adjustable tension device 75 permits 110 the feed rolls to be properly frictionally engaged against the paper strip P, and by means of the knob 76 the tape can be advanced by hand.

The punch spindle is indicated at 6 and 115 the reciprocable punching frame at 5. The gage finger 45 may be raised to permit insertion of the goods from the inner or right side as is necessary when operating on closed vamps or when working around the 120 periphery of the circular opening in the goods. The ordinary form of presser foot is indicated at 46, and the removable punch is shown at 47.

The general operation on closed vamps is 125 as follows: The vamp is introduced over the work arm from the right side, between the end of the arm and the column 2, substantially as shown in Figure 3. To obtain this placement the gage 45 is raised, the goods 130

passed thereunder to the opposite side and then brought backwardly to engage the edge against the work end of the gage. The 5 punching operation is begun at the heel or seamed portion which is laid flatly against the working face of the arm, thus avoiding unnatural buckling or twisting. The punch is now operated, passes through the goods, is then slightly raised to clear the tape which 10 lies upon the punch block and while in the goods, is translated across the tape and block to advance or feed the same. At the end of the feed stroke the punch is entirely withdrawn from the goods and returned to initial 15 position during which time the goods is held by the presser foot 46.

The punching operation continues with the goods always flatly engaged upon the work support without the necessity of unnaturally buckling or twisting at any time. 20 During the whole operation those portions of the goods which are not supported at the upper side of the work arm overhang the arm and are pendently disposed within the 25 throat area herein provided between the end of the work arm and the wall 11 of the column.

To briefly recapitulate, the machine provides the following advantages:

30 A right hand machine permitting introduction of closed work, over the work support from the right hand side of the support;

Ample space between the right or work introducing side of the work support for receiving the goods and permitting free use of the right hand at that side and unobstructed movement of the work;

40 A work support offset and shaped to assist in guiding of the work, particularly when working at the heel or seamed portion;

A work support as a short over-hanging arm of a conformation permitting a natural grasp thereof with the left hand while feeding the work, and laterally angularly disposed with reference to the long axis of the machine and toward the operator for permitting the left hand, wrist and arm to assume a most natural position when holding and feeding the work.

45 Feeding of the paper in the direction of the feed of the goods;

50 Disposal of the work arm or support substantially directly beneath the punch providing a most rigid construction;

Adaptation for operating both open and closed vamps without use of a work plate and therefore without removal and attachment of the same for different kinds of work, 55 permitting gaging at the right side of the work;

Disposal of the incoming and outgoing runs of the paper in unobstructed position, 60 for closed vamp work, to permit the closed vamp to be hung over the work support;

The provision of a machine base the upper surface of which is substantially level with the bench.

Having described the invention, I claim:

1. In a perforating machine, the combination of a base, a punch-carrying arm and a work-supporting arm, both arms being mounted on said base and the end of said work-supporting arm being turned inwardly over said base and beneath said punch-carrying arm, in order to leave a clear and unobstructed space between said end and the base and punch-carrying arm; said space being sufficient to permit the work to be freely suspended from said end and freely handled. 70

2. In a perforating machine the combination of a base, a punch-carrying arm supported on one end of said base and a work-supporting arm supported on the other end of said base, the end of said work-supporting arm being turned inwardly over said base and beneath said punch-carrying arm in order to leave a clear and unobstructed space between said end and the base and punch-carrying arm; said space being sufficient to permit the work to be freely suspended from 85 said end and freely handled. 90

3. In a perforating machine the combination of a column, a punch-carrying arm and a work-supporting arm, both arms being connected to and supported by said column, the end of said work-supporting arm being turned inwardly over and above its main portion toward said column and underneath 100 said punch-carrying arm in order to leave a clear and unobstructed space between said end and the base and punch-carrying arm; said space being sufficient to permit the work to be freely suspended from said end and freely handled. 105

4. The combination of a frame comprising an overhanging arm carrying operating instrumentalities and a lower work-supporting arm having its end turned inwardly in a reverse direction to the overhanging arm to leave a clear and unobstructed space therearound sufficient to permit the work on the end of said lower arm to hang freely and to be handled freely during the operations 110 115 thereon.

5. The combination of a frame comprising an overhanging arm carrying operating instrumentalities and a lower work-supporting arm having its end turned inwardly in a direction reverse to the direction of the overhanging arm, the ends of the two arms extending in opposite directions but being in approximately vertical alignment. 120

6. A machine of the class described comprising a frame made up of an overhanging punch-carrying arm and a lower curved work-supporting arm having its end turned inwardly in a direction reverse to the direction of the overhanging arm to leave a clear 125 130

and unobstructed space permitting work on the end of said lower arm to hang freely and to be handled freely, the end of said lower arm being of a diameter sufficiently small to enter the opening in a closed vamp.

7. The combination of a frame comprising an overhanging arm carrying operating instrumentalities, a lower work-supporting arm having its end turned inwardly in a direction reverse to the direction of the overhanging arm to leave a clear and unobstructed space therearound sufficient to permit the work on the end of said lower arm to hang freely and to be handled freely during the operations thereon and a depending gauge mounted on said overhanging arm for guiding the work on said lower arm; said gauge being resiliently mounted to permit work to be mounted upon said lower arm.

8. The combination of a frame comprising a base, a column extending upwardly therefrom, a punch-carrying arm extending from said column over said base, a work-supporting arm extending upwardly from said base and having its end turned inwardly under said punch-carrying arm and toward said column to leave a clear and obstructed space between said end and said column and said base sufficient to permit work to hang freely on said end and to be handled freely.

9. The combination of a frame comprising an overhanging arm carrying operating instrumentalities, a lower work-supporting arm having its end turned inwardly in a reverse direction and offset laterally to leave a clear and unobstructed space therearound sufficient to permit the work on the end of said lower arm to hang freely and to be handled freely during the operations thereon, and a gauge for guiding the work on said lower arm; said gauge being so arranged as not to interfere with the positioning of the work on said lower arm.

10. In a perforating machine the combination of a base, a punch-carrying arm and a work-supporting arm, both arms being mounted on said base and the end of said work-supporting arm being turned inwardly over said base and beneath said punch-carrying arm but offset laterally in order to leave a clear and unobstructed space between said end and the base and punch-carrying arm; said space being sufficient to permit the work to be freely suspended from said end and freely handled.

11. The combination of a frame comprising an overhanging arm carrying operating instrumentalities and a lower work-supporting arm having its end turned inwardly in a direction reverse to the direction of the overhanging arm and offset laterally to leave a clear and unobstructed space for permitting the work on the end

of said lower arm to hang freely and to be handled freely during the operations thereon.

12. In a machine of the class described, a frame comprising an upper outwardly extending punch-carrying arm and a lower work-supporting arm, the end of said lower arm being turned inwardly in a direction reverse to the direction of said upper arm and into alignment with the punch on said upper arm providing an unobstructed hand rest portion on said lower arm outwardly the work-support and a work-clearance space permitting work to be freely hung and handled on the said end of the lower arm.

13. In a machine of the class described, a base having a work support extending upwardly therefrom, and overhanging the base, said support having a flat work face at the top and having downwardly extending notches at opposite sides, a pair of rollers attached to the base beneath the overhanging portion of the work support, and a tape passed over the top of the work support downwardly at each side thereof, each run of the tape passing between the rollers and each around a respective roller in opposite directions.

14. In a machine of the class described, a base, a work support extending upwardly from and longitudinally of and over said base, means on the work support for guiding a paper strip crosswise thereof, guide elements attached to the base beneath the overhanging portion of the support and adjacent one another, and a paper strip passing across the top of the work support and having its opposite ends converging downwardly at opposite sides of and beneath the support in V-shaped configuration with the convergent portions passing between the guiding elements and around a respective element.

15. In a machine of the class described, a base having a work support extending upwardly therefrom and over the base and having in its top face a recess crosswise of said work support, a block attached within said recess having grooves at opposite ends extending downwardly toward the base, a pair of adjacently disposed rollers attached to the base having their axes at a right angle to the long dimension of the block, a cushion strip extending across the block and disposed in the grooves the opposite ends thereof extending downwardly in V-shaped configuration, at each side of the support, and between rollers, each around a respective roller.

16. In a machine of the class described, a base having a work arm extending upwardly therefrom and horizontally over and spaced from the base longitudinally thereof, a punch block attached to the upper side of

said arm adjacent its end and extending transversely thereof, said block having aligned vertically disposed grooves one in each end face leading toward the base, a 5 pair of guide elements adjacently disposed and attached to the base beneath the arm, a tape extending across the block engaging the grooves and extending downwardly at the sides of the arm, and opposite runs extending 10 convergently downwardly in V-shaped configuration between the guide elements and each around a respective element and in opposite directions.

17. A machine of the class described comprising a frame made up of an overhanging punch-carrying arm and a lower work-supporting arm, the latter arm having its end turned inwardly toward the center of the machine and in a direction reverse to the 20 direction of the overhanging arm and being of a diameter sufficiently small to permit it to enter the opening in a closed vamp, and means for feeding a tape or backer strip across the inwardly turned end of said 25 work-supporting arm without interfering with work thereon.

18. A machine of the class described comprising a frame made up of an overhanging punch-carrying arm and a lower work-supporting arm, the end of said arm being turned inwardly to afford a clear and unobstructed space therearound to permit work 30 to be freely handled therein and being of a diameter sufficiently small to enter the 35 opening in a closed vamp, and means for

feeding a tape or backer strip across the inwardly turned end of said lower arm in the same direction as the normal line of feed; the opposite runs of said tape on the two sides of said lower arm being converged 40 downwardly in V-shaped configuration to avoid interference with work hung on the end of said lower arm.

19. A machine of the class described comprising a frame made up of an overhanging punch-carrying arm and a lower work-supporting arm having its end turned inwardly in a reverse direction to the overhanging arm, and means for feeding tape or backer 45 strip over the end of said lower arm in a direction parallel with the normal line of feed of the work without interfering with work hung on the end of said lower arm.

20. A machine of the class described comprising a frame made up of an overhanging punch-carrying arm and a lower work-supporting arm having its end turned inwardly in a reverse direction, and means for feeding a tape or backer strip over the end of 50 said lower arm in a direction parallel with the normal line of feed; the opposite runs of said tape on the two sides of said lower arm being converged 55 downwardly in V-shaped configuration to avoid interference with work hung on the end of said lower arm.

In witness whereof, I hereunto subscribe my name.

WILLIAM F. LAUTENSCHLAGER.
